UNITED STATES PATENT OFFICE.

EARLE M. JONES, OF MINNEAPOLIS, MINNESOTA, ASSIGNOR TO O. B. McCLINTOCK COMPANY, OF MINNEAPOLIS, MINNESOTA, A CORPORATION OF MINNESOTA.

DESIGN FOR A BURGLAR-ALARM HOUSING.

Application filed February 2, 1922. Serial No. 498. Term of patent 14 years.

To all whom it may concern:

Be it known that I, EARLE M. JONES, a citizen of the United States, residing at Minneapolis, in the county of Hennepin and State of Minnesota, have invented a new, original, and ornamental Design for Burglar-Alarm Housing, of which the following is a specification, reference being had to the accompanying drawing, forming part thereof.

The figure is a perspective view of a burglar alarm housing showing my new design.

I claim:

The ornamental design for a burglar alarm housing, as shown.

EARLE M. JONES.
